UNITED STATES PATENT OFFICE.

MARI E. WOLVEKAMP, OF OAKLAND, CALIFORNIA.

SOUND CONCENTRATOR.

Application filed March 28, 1924. Serial No. 702,064.

This invention relates to improvements in sound-concentrating instruments.

One object of the invention is to concentrate the sound-waves for the purpose of obtaining a stronger effect at the same distance or the same effect at a greater distance.

Another object of the invention is to use a sound-concentrator instead of a horn to avoid distortion of the musical quality by resonance.

10 A further object of the invention is to provide a simple and practical instrument to determine the direction of an invisible sound-source.

15 Other objects and advantages will appear in the following specification, reference being had to the accompanying drawing, in which:—

Figure 1 is a side elevation showing a 20 sound-concentrator consisting in two concave spherical reflectors in combination with the sound-conduit of a phonograph-recorder.

Figure 2 is a side elevation showing a 25 sound-concentrator consisting in two concave spherical reflectors applied to a telephone transmitter.

Figure 3 is a sectional view of a sound-concentrator consisting in two concave parabolic reflectors adapted for hearing of and 30 determining the direction of distant sounds, showing also the double reflection of the sound-waves.

Figure 4 is a diagram of the sound-concentrator shown in Figure 2, illustrating the 35 double reflection of the sonorous waves and the relative positions of the principal and conjugate foci.

The underlying principle of this invention 40 is to converge the sound-waves to a focus by means of a concave spherical or parabolic reflector and to throw back these concentrated sound-waves by means of a second concave spherical or parabolic reflector through a 45 hole at the pole or vertex in the first and larger reflector.

For the proper arrangement of the two sound-reflectors it is important to know the 50 exact positions of the foci and therefore I prefer reflectors of such a shape that their principal foci are in the planes and at the centers of their circular boundaries.

The diameters of the circular boundaries of such spherical or parabolic reflectors are therefore equal to respectively $2\sqrt{3}$ and 4

times the distance from the focus to the pole or vertex of the reflectors.

The most practical materials for these reflectors are metal, wood, ebonite, and glass.

In Figure 1 a spherical reflector 1 reflects the sound to a little spherical reflector 2, 60 which is supported by bars 3 and reflects the sound through a hole in reflector 1 leading inside the sound-conduit S C of a phonograph-recorder.

If a person sings before the large reflector, 65 the sonorous waves will be reflected and at the same time converge for example to a point identical with the principal focus of the little reflector and hence parallel sound-waves will be thrown back through the hole at the 70 pole of the large reflector. A little parabolic reflector may be substituted for the spherical reflector.

It is easy to see that such a sound-concentrator will have a strong concentrating power, 75 dependent upon the diameters of the two reflectors.

Such a sound-concentrator is more effective than a horn of the same, or, as I found, of twice as large diameter.

Recent investigations by Foley and Cloud (The Physical Review, vol. 22, second series No. 1, p. 73) show that the so-called "condensing power" of horns having a large angle of flare may be partly imaginary.

J. H. Cloud showed that while a horn doubled the intensity of the sound emitted by an organ pipe, it acted merely as a resonator.

A sound-concentrator not only is more effective than a horn, but it does not distort the musical quality by resonance.

In Figure 2 the spherical reflector 4 reflects the sound to the little spherical reflector 5, which is supported by bars 6 and throws 95 the sound-waves back through the mouth-piece M of a telephone transmitter T.

In Figure 3 a parabolic reflector reflects the sound-waves to a little parabolic reflector, which in turn reflects the sound-waves into 100 the ear-tube and handle. If the sound comes from a distant source, the parallel sound-waves will be reflected to the focus F, which in turn may be made the focus of the little reflector and hence parallel sound-waves will 105 be sent through the ear-tube H.

Such a sound-concentrator is simple in arrangement and effective and may also be

useful in determining the direction of invisible sound-sources as for example of ships in a fog or of airships and aeroplanes at night.

By moving the little parabolic reflector a little farther from the vertex V , convergent sound-waves will be reflected through the ear-tube.

A better focussing may be obtained by using a little spherical reflector instead of the parabolic one.

In Figure 4, D and E denote opposite points on the circular boundary of the large reflector 4 with its principal focus F on the straight line DE and equidistant from the center of curvature C and the pole P .

For the little spherical reflector 5 the corresponding points are at d, e, f, c , and p .

If the source of the sound S is nearby on the principal axis, the sound-waves will be reflected to the conjugate focus s between C and F .

If s is situated between the center of curvature c and the focus f of the little reflector, the sound-waves will converge to a point X .

Following equations:—

$$\frac{1}{SP} + \frac{1}{sP} = \frac{1}{FP} \text{ and } \frac{1}{Xp} + \frac{1}{sp} = \frac{1}{fp}$$

are only approximately accurate on account of spherical aberration, although sufficiently accurate for all practical purposes.

The distances of the conjugate focus s to the principal foci F and f are in general very small.

If for example SP is equal to $10 FP$ and Xp to $7 fp$, sF will be equal to $1/9 FP$ and sf to $1/6 fp$.

If X is at the center of the diaphragm of the transmitter, the strongest effect will be obtained.

A similar sound-concentrator in combination with an ear-tube may be practical for deaf people.

While the construction and arrangement of the sound-concentrators as herein described and claimed, is that of a generally preferred form, obviously modifications and changes can be made without departing from the spirit of the invention or the scope of the claim.

I claim:—

In a sound-concentrator, the combination of two open parabolic reflectors of distinctly different sizes, the concave surfaces of these mainly empty reflectors being opposite to one another, the vertex and principal focus of both reflectors being on the same principal axis, and the large reflector provided with a hole at its vertex for the passage of the sound, substantially as set forth.

In testimony whereof I affix my signature.

MARI E. WOLVEKAMP.
